UNITED STATES PATENT OFFICE.

FREDERICK W. COLE, OF NEWTON, MASSACHUSETTS, ASSIGNOR TO GAMEWELL FIRE ALARM TELEGRAPH COMPANY, OF NEWTON UPPER FALLS, MASSACHUSETTS, A CORPORATION OF NEW YORK.

LOCK FOR FIRE-ALARM BOXES.

1,183,830.

Specification of Letters Patent.

Patented May 16, 1916.

Application filed April 18, 1914. Serial No. 832,943.

To all whom it may concern:

Be it known that I, FREDERICK W. COLE, a citizen of the United States, residing at Newton, in the county of Middlesex and 5 State of Massachusetts, have invented an Improvement in Locks for Fire-Alarm Boxes, of which the following is a specification.

The doors of fire-alarm boxes are sometimes locked by means of more or less complicated locking-mechanisms adapted to be operated by a key which is removable from the lock; and sometimes by a bolt having connected with it a rotatable handle by 10 which it is operated, as for instance, in those types of fire-alarm boxes commonly known as keyless boxes; and sometimes by a lock having a key arranged in connection with it, which key is inclosed by a guard having 15 a frangible front plate. In the latter case the key is sometimes inserted and left in the lock and sometimes is removed and adapted to be inserted. Many objections are urged 20 against these various types of locking- 25 means, some of which are real and some imaginary, but the least objections are urged against the latter type, wherein the key is inserted and left in the lock and inclosed by a guard.

This invention relates to the latter type 30 of locks for fire-alarm box doors, and has for its object the provision of a simple, cheap yet efficient form of device which may be easily and quickly applied to a door and 35 is not liable to get out of order, and furthermore, may be readily applied to old types or forms of fire-alarm box doors, first above referred to, many of which are in use at the present time.

The invention consists in arranging a 40 sliding latch-bolt on the inside of the door, in a suitable bolt-casing, and in permanent operative engagement with a key by which it may be operated, and in employing a common 45 form of key-blank having a bit which may be projected through the usual key-hole, and then turned to bring its bit out of alignment with the key-hole and into operative engagement with the latch-bolt, and providing 50 means to thereafter hold the bit of the key in approximately such position so as to prevent it from being moved again into alignment with the key-hole, thus to prevent subsequent withdrawal of the key. The

means for preventing the bit of the key 55 from being moved into alignment with the key-hole involves its association with the latch-bolt mechanism in some manner which necessitates the key being projected into the key-hole and turned before the latch-bolt 60 mechanism is secured to the inside of the door, but any equivalent means falls within the scope of my invention which may be brought into position after the key has been introduced and turned to prevent the bit 65 of the key from being again brought into alignment with the key-hole.

The outer end or hand-engaging portion of the key is inclosed in a key-guard arranged on the outside of the door, which 70 key-guard has a frangible front, such as a glass plate, which is designed to be broken to obtain access to the key.

Figure 1 is a front elevation of a fire-alarm box with key-guard and key embodying this invention. Fig. 2 is an enlarged rear side elevation of a portion of the door and the lock and key in permanent engagement with the lock. Fig. 3 is a front elevation of the lock and key. Fig. 4 is a plan view of the lock and key. Fig. 5 is an end elevation of the lock and key. Figs. 6 and 7 are modified forms of my invention.

The latch-bolt mechanism here shown comprises a latch-bolt 10, which is supported by and arranged to slide in a bolt-casing comprising a back-plate 15, and a pair of supporting cross-pieces 16, 17, arranged on one and the same side of said plate and near the ends thereof, so as to 85 occupy a position between said plate and the inside of the door 12, said cross-pieces each having a transverse recess corresponding to the transverse sectional shape of the latch-bolt 10, which recesses are arranged in horizontal alignment to receive and permit free sliding movement of the latch-bolt. The back-plate and cross-pieces are or may be held assembled with the latch-bolt arranged in the recesses of the cross-pieces, by screws 90 21, or equivalent means which extend through holes in the back-plate and cross-pieces and into or through holes in the door 12, so that the bolt-casing is thus secured to the inside of the door by the means employed for holding its component parts 100 assembled. A spring 18 is connected at one end to a pin or projection 19 on the latch-

bolt 10, and at the other end to the back-plate 15, which spring acts to throw the latch-bolt in an outward direction or into locking position. This outward movement 5 of the latch-bolt is limited by a lug 20 arranged on the back-plate and projecting forward into the path of movement of said pin. Movement of the latch-bolt in the opposite direction is limited by said pin en- 10 gaging the cross-piece 17. Said latch-bolt has arranged along its under side one or more notches 22, three being here shown, and said latch-bolt and its casing are so arranged on the inside of the door that one 15 of said notches occupies a position just above the top of the usual key-hole 23, in the door. Three notches are here provided to accommodate different fire-alarm box doors now in common use, which have their 20 key-holes arranged at different distances from the edge.

25 represents a key, of simple form, having a single flat bit 26, and having the end-portion 27 of its shank extended beyond the bit. Such a key may be an ordinary key-blank from which keys are usually made. This key will be projected through the usual key-hole 23, in usual manner, and its end-portion 27 will enter one of the holes 30 28, in the back-plate 15; then said key will be turned a half revolution to bring its bit up into vertical position and above the key-hole for engagement with one of the notches in the latch-bolt; and then the component 35 parts of the bolt-casing with latch-bolt, are arranged on the inside of the door with the latch-bolt in engagement with the bit of the key and the parts thus assembled are secured in place by the screws 21. When 40 the key is turned to the right, in the usual manner, the bolt will be moved to withdraw it from locking-position, and subsequently will be caused to return to locking-position by means of the spring 18, when pressure 45 upon the key is relieved.

As the movement of the bolt is limited in both directions the key will be permitted to turn only through a short arc in either direction, and while such movement of the key is sufficient to move the latch-bolt it is not sufficient to disengage the latch-bolt, to admit of its being again brought into alignment with the key-hole, hence engagement of the key with the latch-bolt becomes permanent, and subsequent withdrawal of the key is prevented.

In lieu of holding the key with its bit out of alignment with the key-hole by this particular means other means may be employed for accomplishing the same result; and referring to Fig. 6 the latch-bolt has a long notch with a shoulder at one end for engagement with the bit of the key, and a pin 35 which may be on the back-plate 15, or on the inside of the door, is arranged on

that side of the bit of the key opposite the shoulder of the notch in the latch-bolt, thereby to limit the movement of the bit of the key through a short arc and prevent it from being brought into alignment with 70 the key-hole. Or, the modified form shown in Fig. 7 may be employed wherein two pins 36, 37, arranged at opposite sides of the bit of the key are provided, which pins may be arranged on the inside of the door, or on the 75 back-plate of the latch-bolt mechanism. In all these instances it will be observed that the key is first introduced and its bit brought into approximately vertical position above the key-hole, and out of alignment therewith, and then the latch-bolt mechanism is placed in position on the inside of the door and when secured thereto the key is held against being again turned to bring its bit into alignment with the key- 80 hole, which it will be understood is the important feature of this invention.

30 represents a usual form of key-guard which may be applied to the outside of the box-door, over the key-hole, to form a chamber to receive the outer or hand-engaging portion of the key 25, said key-guard having a frangible front-plate designed to be broken to obtain access to the key.

My invention is to be especially contrasted 95 with a key that is inserted in the lock and trapped, and is subsequently withdrawn when released.

I claim:-

1. A fire-alarm box door having a key-hole, and a key-guard arranged on the outside of the door over said key-hole, latch-bolt mechanism comprising a sliding latch-bolt and bolt-casing arranged on the inside of said door with a spring for moving said 100 latch-bolt into locking-position, and a key permanently arranged in the key-hole with its bit out of alignment therewith, said key being co-operatively assembled with the component parts of the latch-bolt mechanism 105 and held in permanent operative engagement with the bolt, in all positions said bolt may occupy.

2. A fire-alarm box door having a key-hole, a key-guard arranged on the outside of the box door over said key-hole, a sliding latch-bolt having a plurality of notches, and a bolt-casing having a corresponding number of holes arranged on the inside of the door with a spring for moving said bolt into 115 locking position, means for limiting the sliding movement of said bolt in both directions, and a key permanently arranged in the key-hole with its bit out of alignment therewith and in engagement with one of the notches 120 in the latch-bolt, and its end-portion in engagement with one of the holes in the bolt-casing, the sliding movement of the latch-bolt being limited to permit movement of the key through a short arc only, whereby it 125

is retained in permanent engagement therewith, in all positions said bolt may occupy.

3. The combination with a fire-alarm door having a fragile guard member upon its outer face, and a keyhole located within the guard, of a lock including a movable locking element, and a key having its head portion disposed within the guard, and its bit in operative engagement with the locking element, and means for preventing the disengagement of the key from the locking element except upon disassemblage of the lock.

4. A lock including a casing secured to a member to be locked, said member being provided with a keyhole leading into the casing, a locking element movable in the casing, a key having its bit engaging with the locking element, said bit being disengageable from the locking element after being turned through an arc of definite length, and means for permanently preventing the movement of the bit through an arc of the length required to disengage the bit from the locking element, whereby the key may be

withdrawn from the casing, only upon the 25 disassemblage of the lock.

5. A lock including a casing secured to a member to be locked, said member being provided with a keyhole leading into the casing, a locking element movable in the casing, a 30 key having its bit engaging with the locking element, said bit being disengageable from the locking element after being turned through an arc of definite length, stop means for limiting the movement of the locking 35 element in each direction to points whereat the bit remains positively engaged with the locking element, and is consequently permanently maintained against withdrawal from the casing.

In testimony whereof, I have signed my name to this specification, in the presence of two subscribing witnesses.

FREDERICK W. COLE.
